UNITED STATES PATENT OFFICE.

GEORGE FREDERICK WILLIAMSON, OF MIDLAND FOUNDRY, WELLINGBOROUGH,
ENGLAND.

KEY FOR SECURING RAILWAY OR LIKE RAILS IN THEIR SUPPORTING-CHAIRS.

1,199,139.

Specification of Letters Patent. Patented Sept. 26, 1916.

Application filed April 24, 1916. Serial No. 93,283.

To all whom it may concern:

Be it known that I, GEORGE FREDERICK WILLIAMSON, a subject of the King of Great Britain and Ireland, residing at Midland 5 Foundry, Wellingborough, England, have invented certain new and useful Improvements in Keys for Securing Railway or like Rails in Their Supporting-Chairs, of which the following is a specification.

This invention for improvements in keys for securing railway or like rails in their supporting chairs relates to metal chair-keys with expanding or tightening wedges and has for its object to provide an improved key 15 of this type that shall be simple in construction and capable of being easily inserted and firmly secured in position between the chair jaw and web of the rail.

A further object of the invention is to 20 provide a wedge which when driven horizontally into the key shall be self-locking and shall expand the key against the rail and chair jaw causing the key to exert a permanent or sustained pressure or grip on the rail, thus avoiding the so-called rail creeping and 25 other troubles caused by keys working loose or in the case of metal keys, retaining a permanent set.

With the above objects in view, I construct 30 the improved metal key of tubular form preferably with a longitudinal slit to allow of expansion or contraction and I provide inside the key horizontal guides extending longitudinally thereof for receiving the expanding wedge which is driven horizontally along the guides in the key and produces a lateral expansion of the key. Means are also provided in the key to bend or distort 35 portions of the wedge as it is driven so as to prevent its ready withdrawal or in other words, lock it in position. In use, the key is inserted in a similar manner to the wooden key between the chair jaw and web of the rail, being preferably shaped to bear against 45 the head and foot of the rail.

The invention is hereinafter described 50 with reference to the accompanying three sheets of illustrative drawings containing eleven figures, in which the reference letters have the same signification throughout.

Figure 1 is a transverse section taken 55 through a permanent way rail adjacent the rail chair, illustrating in end elevation a rail chair with a metal chair key and wedge constructed according to this invention in

position between the chair jaw and rail. Fig. 2 is a plan of the rail chair and a portion of the rail with the improved chair-key and wedge in position. Fig. 3 is a side elevation of the parts illustrated in Figs. 1 and 60 2. Fig. 4 is a longitudinal sectional plan taken along the line 3—3 Fig. 3. Fig. 5 is a separate plan view of the expanding or 65 tightening wedge. Fig. 6 is an end elevation of the chair key illustrating the opposite end to that shown in Fig. 1. Fig. 7 is a longitudinal section of the chair key. Fig. 8 is a transverse section taken through the rail and the outer jaw of a rail chair and illustrating in end elevation a slightly modified 70 form of key. Fig. 9 is a horizontal section taken through the rail web and outer chair jaw illustrating in plan the modified form of key shown in Fig. 8. Fig. 10 is a sectional plan illustrating portions of a rail, a chair 75 which is narrow between the jaws and a further modified form of key applicable to such a chair. Fig. 11 is a separate view of the wedge used with the type of key illustrated in Fig. 10.

Referring to Figs. 1 to 7, the improved key *a* as shown is tubular or hollow, similar in shape externally to the ordinary wooden key but shorter in length, and slit longitudinally at *b* along the center of the crown or upper wall. In the interior of the hollow key, longitudinal guide ribs *c* are cast or formed in pairs and constitute opposite guide-ways inside the key, said guide-ways being located at half the depth of the key or thereabout 85 and serving to guide and retain the expanding wedge *d* in position. By suitably thickening the walls of the key the guide ways are made slightly convergent from the inlet 90 or driving end of the key to the opposite end. Strengthening ribs *c*¹ may be cast at intervals in the length of the key and preferably run transversely from the guide ribs *c* gradually merging into the wall of the key. At the 95 far end of the guide-ways in the key, deflecting guide pieces *c*² are provided which form a continuation of the guide-ways *c* said guides *c*² having curved slots *c*³ clearly shown in Fig. 4 for a purpose hereinafter described. A suitable material from which the key may 100 be manufactured is malleable cast iron, but steel, semi-steel or other metals may be employed. The key is driven in between the web of the rail and the chair before the wedge is driven home into the key, the slot 105 110

b affording or giving sufficient resiliency for this purpose.

The wedge *d* is formed of a steel plate of sufficient width to extend across the key and fit between the guide-ways inside, and of a length greater than the length of the key, the wedge being slit longitudinally from one end to form a pair of side prongs *e e* with a central extension or prong *f* between them which after the wedge is driven home is arranged to project a sufficient distance beyond the end of the key so that it can be easily hit with a hammer or other tool when it is desired to release the wedge and thereby allow the rail key to be withdrawn. As the wedge is driven in the key the prongs *e* are bent or distorted by the guide pieces *c²* to secure the key in position, while the central extension *f* of the wedge passes through a straight slot *c⁴* between the guides *c²*. As the key is slit along the top its sides are forced apart by the driving in of the wedge which is suitably tapered and cooperates with the suitably tapered guide-ways.

In order to impart resiliency to the wedge *d*, it may be arched or cambered transversely along the solid portion thereof.

The key *c* is preferably cast with ribs or enlargements *g* at the ends on the chair side to engage the end faces of the chair jaw *h*, when the key is fixed in position and thus prevent longitudinal movement of the key. In the modified form of construction shown in Figs. 8 and 9, a longitudinal shoulder or projection *i* is cast on the chair jaw side of the key and the chair jaw *h* has a rabbeted recess formed therein at its upper edge to receive said projection, which forms an additional support for the key against lateral stresses. The key is also made with a solid crown for the greater part of its length, but preferably slotted near the ends as shown at *b b*.

In the modified form of key shown in Figs. 10 and 11 which is applicable to a chair with narrow jaws, the key is formed with only two slots *c³ c⁴*, the slot *c⁴* which corresponds to the central slot in the other forms being in this case curved in a similar manner to the slot *c³*. A wedge for use with this key as illustrated in Fig. 11 has two prongs *e f* both of which are bent in the

curved slots when the wedge is driven in to lock the wedge in position. The larger 55 prong *f* also projects beyond the end of the key so that it can be hit with a tool to release the wedge.

In the different forms of key described the walls are made sufficiently thick to 60 give the required strength without depriving the key of the necessary resiliency to allow of expansion and the thickness of different parts of the key may be varied to enable it to present at all points adequate 65 resistance to compression stresses.

What I claim and desire to secure by Letters Patent is:—

1. An improved metal key with expanding wedge for securing railway or like rails 70 in their supporting chairs consisting of a tubular key adapted to fit in the space formed between the chair jaw and the rail and be expanded by a wedge driven between guides formed inside the key. 75

2. An improved metal key with expanding wedge for securing railway or like rails in their supporting chairs, consisting of a tubular metal key split longitudinally along the crown or upper wall and provided internally with horizontal guide ribs for guiding the expanding wedge, and means for bending portions of the wedge as it is driven to secure the same in position. 80

3. An improved metal key with expanding wedge for securing railway or like rails in their supporting chairs consisting of a tubular metal key split longitudinally along the crown or upper wall and provided internally with horizontal guide ribs for 90 guiding the expanding wedge and a bendable locking prong and a driving out prong on said wedge, substantially as described. 85

4. An improved metal key with a multi-pronged expanding wedge for securing railway or like rails in their supporting chairs, consisting of a tubular metal key, split longitudinally along the crown or upper wall and provided internally with horizontal guide ribs for guiding the expanding wedge, 100 said guides having terminal straight and curved guides for guiding and securing said expanding wedge, substantially as described.

In testimony whereof I have affixed my signature.

GEORGE FREDERICK WILLIAMSON.
